GYROSCOPIC TOY

Filed Sept. 20, 1946

UNITED STATES PATENT OFFICE

2,513,066

GYROSCOPIC TOY

Edward T. Stahl, Santa Ana, Calif.

Application September 20, 1946, Serial No. 698,273

2 Claims. (Cl. 46—50)

1

This invention relates to a toy and more particularly and specifically to a new and improved gyroscopically balanced walking toy which has as its primary object the provision of a toy of the character described which is a rope walking toy maintained in an upright position by a fluid operated gyroscope.

Another object of this invention is the provision of such a toy which could be of educational value to children.

Still another object of this invention is the provision of a toy of the character described which is of simple, durable and inexpensive design.

Further advantages and improvements of this invention will readily appear to those skilled in the art upon examination of the following description when read in the light of the accompanying drawings in which:

Fig. 1 is a vertical section taken through a side elevation.

Fig. 2 is a horizontal section taken on line 2—2 looking in the direction indicated by the arrows.

Fig. 3 is a vertical section taken on line 3—3 of Fig. 1 looking in the direction indicated.

Fig. 4 is a top plan view of the toy.

Referring now to the drawings A designates the main body of the toy which in this instance is designed to represent a clown but could be made in any form without departing from the spirit of the invention.

The main body A is formed from two sections 1 and 2 which are separably connected by a suitable means such as the inset screws illustrated in the accompanying drawings.

A vertical slot 5 carried upwardly from the center of the base 6, of the body A, houses a grooved wheel 7 which is rotatably mounted on the horizontal pinions 8 and 9. This wheel supports the toy body on the flexible cord or cable 10 which is secured to a stationary object at 11 and grasped by the operator at the other end thereof. The operator, by raising and lowering the free end of the cord 10, will cause the toy to move back and forth on cord 10.

Formed within the toy body and running between both halves 1 and 2 is a horizontal cavity B whose axial center is on line with that of the body A.

Secured within body A adjacent the upper and lower sides of said cavity and on its vertical center line are two bearings 12 and 13 which receive a shaft 14 on which is mounted for horizontal rotation a gyroscopic wheel C. This wheel is provided about the circumference of its upper side with a series of notches or buckets 15.

2

Originating at the top of the head of the body, which is formed to provide a mouthpiece, and running downwardly and rearwardly to the outer, upper edge of cavity B is a tubular passage D which terminates at the cavity in a restricted throat or nozzle 16 which is disposed downwardly to and in the direction of rotation of the wheel buckets.

The operator, by blowing a blast of air into passage D will cause the rotation of the gyroscopic wheel C as the blast of air is directed against the buckets 15 by the nozzle 16. When the operator removes his mouth from the mouthpiece, some of the blast of air which causes the rotation of the gyroscope wheel will have leaked out between the opposing faces of the sections 1, 2, of the body A, and the remaining portion of the blast will escape through the passageway D.

This rotation of the wheel C enables the toy A to maintain an upright position on cable 10 by reason of gyroscopic principle, and successive blasts of air at spaced intervals will maintain the toy A in its upright position on the cable 10.

It can be seen that examination and repair to the working parts can be easily accomplished by the removal of 1 from 2.

Having thus described and explained this invention I claim:

1. In a gyroscopic toy, a body including a pair of sections arranged in facing relation with respect to each other and secured together, the opposing faces of each of said sections being provided with a semi-cylindrical recess therein, said recesses cooperating to provide a substantially cylindrical cavity in said body, and a gyroscope positioned within said cavity and mounted on said body for rotation about an axis extending longitudinally of said body, said gyroscope including a wheel having a plurality of buckets positioned adjacent the periphery thereof for effecting the rotation of said gyroscope as a jet of air impinges said buckets, one section of said body being provided with a tubular passageway therethrough having one end in communication with the atmosphere and having the other end in communication with said cavity, and a mouthpiece secured to said one section adjacent said one end of said passageway, whereby the gyroscope is rotated upon blowing into said one end of said passageway.
2. In a gyroscopic toy, a body including a pair of sections arranged in facing relation with respect to each other and secured together, the opposing faces of each of said sections being provided with a semi-cylindrical recess therein, said recesses cooperating to provide a substantially cylindrical cavity in said body, and a gyroscope positioned within said cavity and mounted on said body for rotation about an axis extending longitudinally of said body, said gyroscope including a wheel having a plurality of buckets positioned adjacent the periphery thereof for effecting the rotation of said gyroscope as a jet of air impinges said buckets, one section of said body being provided with a tubular passageway therethrough having one end in communication with the atmosphere and having the other end in communication with said cavity, and a mouthpiece secured to said one section adjacent said one end of said passageway, whereby the gyroscope is rotated upon blowing into said one end of said passageway.

cylindrical cavity in said body, a gyroscope positioned within said cavity and mounted on said body for rotation about an axis extending longitudinally of said body, said gyroscope including a wheel having a plurality of buckets positioned adjacent the periphery thereof for effecting the rotation of said gyroscope as a jet of air impinges said buckets, one section of said body being provided with a tubular passageway therethrough having one end in communication with the atmosphere and having the other end in communication with said cavity, and a mouthpiece secured to said one section adjacent said one end of said passageway whereby the gyroscope is rotated upon blowing into said one end of said passageway, said other end of said passageway being restricted to provide a nozzle for directing the air blown into said passageway against said buckets.

EDWARD T. STAHL.
